Primary Examiner — Prabhakar Deshmukh(74) *Attorney, Agent, or Firm* — The Dobrusin Law Firm, PC(57) **CLAIM**

The ornamental design for a control and tablet device, as shown and described.

DESCRIPTION

FIG. 1 is top front perspective view of a control and tablet device showing our new design;

FIG. 2 is a top plan view thereof;

FIG. 3 is a top rear perspective view thereof;

FIG. 4 is a side view thereof; and,

FIG. 5 is a bottom plan view thereof.

The broken lines indicate unclaimed portions and form no part of the claimed design.
